Adam Weber.

UNITED STATES PATENT OFFICE.

ADAM WEBER, OF NEW YORK, N. Y.

IMPROVEMENT IN SETTING GAS-RETORTS.

Specification forming part of Letters Patent No. 36,119, dated August 5, 1862.

To all whom it may concern:

Be it known that I, ADAM WEBER, of New York, in the county and State of New York, have invented a new and useful Improvement in Gas-Retort Benches; and I hereby declare that the following is a full and exact description of the same, reference being had to the accompanying drawings, and to the letters of reference marked thereon.

Figure I represents a cross-section. Fig. II shows a longitudinal section at the line V W, Fig. I.

Similar letters represent similar parts.

The nature of my invention consists in the arrangement of suitable girders supported by cross-ties resting on an arch or arches built over the fire-place in such a manner that each retort shall be supported by itself without resting or bearing upon any other retort, whereby the clay retorts are less liable to break, and each retort may be taken out and replaced without disturbing any other retort.

In the accompanying drawings, A A' represent clay retorts made in the usual manner. B is the fire-place, over which, in several places, arches C C are built. Upon these arches cross-ties D D are placed, carrying upright supports or stands H. On the top of these stands H girders K K are placed, whose extreme ends rest on suitable projections, F, made on the side walls of the oven. On the top of these girders K, and above the supports H, similar supports, M, are placed, upon which girders L are fastened. On these girders K and L clay plates or tiles N N are placed, extending from one girder to the other, fastened to the same and forming a bed for the retorts A to rest upon, and at the same time to protect the under side or bottom of the retorts from the action of the fire. By this arrangement the retorts will be supported independent of each other, each re-

tort resting upon separate girders, and which latter are supported by arches built over the fire-place.

By the arrangement of arches over the fire-place to take the weight and support the retorts, I am able to increase the fire-place to any desired extent.

The two lower retorts, A', rest upon suitable brick-work upon plates or tiles E, which said plates or tiles E protect the bottom of these retorts and form the top of the return-flues P.

The fire and heat pass out of the fire-place B between the arches C, act upon the retorts, and pass through openings Q downward into the return-flues P, and from there into the chimney J. To protect the lower retorts, A', at their sides next the fire from the extreme heat, plates G, corresponding in form to the shape of the retorts, are arranged and fitted against those parts most exposed.

The usual plan of setting clay retorts has been to make the lower retorts support the upper retorts, by which arrangement the whole oven must be broken up and all retorts taken out whenever only one of the lower retorts requires to be replaced, while by my improved arrangement any one of the retorts can be taken out and replaced without disturbing the others.

What I claim as my invention, and desire to secure by Letters Patent, is—

The herein-described arrangement of setting clay retorts upon separate girders, said girders being supported by an arch or arches built over the fire-place and arranged in the manner and for the purpose substantially as set forth.

ADAM WEBER.
